UNITED STATES PATENT OFFICE.

GEORGE W. STEPHENSON, OF OKLAHOMA, OKLAHOMA.

PHOTOGRAPHIC DEVICE.

No. 893,396.

Specification of Letters Patent.

Patented July 14, 1908.

Application filed April 1, 1907. Serial No. 365,712.

To all whom it may concern:

Be it known that I, GEORGE W. STEPHENSON, a citizen of the United States, and resident of Oklahoma city, in the county of Oklahoma and State of Oklahoma, have invented an improvement in Photographic Devices, of which the following is a specification.

My invention is an improvement in photographic devices and consists in certain novel 10 constructions and combinations of parts hereinafter described and claimed.

Referring to the drawings forming a part hereof, Figure 1 is a perspective view of my improvement. Fig. 2 is a vertical section. Fig. 3 is a section on the line 3—3 of Fig. 2. Fig. 4 is a section on the line 4—4 of Fig. 2. Fig. 5 is a section on the line 5—5 of Fig. 2. Fig. 6 is a section on the line 6—6 of Fig. 4. Fig. 7 is a section on the line 7—7 of Fig. 6. Fig. 8 is a section on the line 8—8 of Fig. 6. Fig. 9 is a section on the line 9—9 of the same figure. Fig. 10 is a perspective view of the fingers for transferring the paper from the cutting device to the developing solution; 25 and Fig. 11 is a detail sectional view of a part of Fig. 10.

My invention is especially adapted for making photographic prints of records, and for developing and fixing the print at a single 30 operation.

In the present embodiment of the invention, a casing A is provided, comprising the base a, and the side walls a'. A front wall a² connects the sides, and is provided with a 35 rectangular opening a³ therethrough, the said opening being adapted to permit the passage of the lens tube b, the bellows b' being arranged partly within the casing, the front of the bellows and the lens tube being 40 carried by a board b² slideable upon a bracket b³ secured within the casing and projecting therefrom.

On the front of the board b² are arranged 45 brackets b⁴, each bracket being provided with a longitudinal slot b⁵, whose lower edge is notched as at b⁶, and a mirror or other reflecting medium b⁷ is supported by the brackets, the said mirror or reflecting medium being provided with trunnions b⁸ for 50 engaging the notches, whereby the said mirror may be adjusted toward and from the board b², the angle of inclination of the mirror with respect to the lens being varied by rocking it upon its trunnions.

Below the lens tube opening a³, the base of 55 the casing is extended forwardly, and the

side walls are inclined, and a door a⁶ is hinged to the front wall and rests on the inclined sides for a purpose to be hereinafter described. A record supporting frame a¹² is 60 hinged at a¹³ to the casing above the door a⁶, the said supporting frame comprising side arms a¹³, between which is hinged a rocking support a¹⁴ having flanged ends as clearly shown in Figs. 1 and 2. The rocking support a¹⁴ is journaled on a bar or rod a¹⁷ extending through the side arms of the frame, and having nuts a¹⁸ threaded on the outer 65 ends thereof. By loosening the nuts the support may be placed in suitable position, 70 and after the nuts are tightened, if will be retained in its adjusted position. Notched arms a¹⁵ are secured to the supporting frame a¹² on each side thereof, and engage pins a¹⁶ on the side walls of the casing, to retain the 75 supporting frame in its adjusted position.

The casing A is provided with a top a⁴, and the back of the casing is formed by a plurality of doors, one of the doors a⁷ being hinged to the top, another a⁸ being arranged 80 at the base, and the intermediate space being closed by two doors a⁹, a¹⁰, all of the doors being secured by hooks and eyes a¹¹.

A partition a¹⁰ is arranged above the bellows, the said partition being provided with 85 a slit a²⁰ at the back thereof, and within the compartment formed above the partition is journaled a roller C for supporting the sensitized paper. The sensitized paper extends from the roller over a guide roller c arranged 90 adjacent to the slit before mentioned, and downwardly behind the bellows to a feeding mechanism to be hereafter described.

A curtain c² is arranged in front of the paper, within the bellows chamber, the said 95 curtain winding upon a spring roller c' of ordinary construction, and being guided by guides c³ secured to the side walls of the casing.

The feeding mechanism comprises a roller 100 c⁴, journaled in the walls of the casing transversely thereof, and provided on its outer end with a handle c⁸, the said roller having a ratchet disk c¹⁰ secured thereto outside of the casing, and engaged by a pawl c⁹, for 105 normally fixing the roller. Upon the roller are adjustably mounted feeding disks c⁵, the said disks comprising the disk portion proper and hollow hubs c⁶, through which the roller c⁴ passes, the said hubs being movable on the 110 roller and retained in their adjusted position by the set screws c⁷. Other disks c¹¹ coop-

erate with the feeding disks c^5 , the said disks c^{11} being journaled on arms c^{12} , which are adjustable on a rod c^{13} arranged at the lower edge of the bellows, the arms being retained in their adjusted position on the rod by means of set screws c^{14} . Springs c^{15} are secured to the door a^9 of the casing, and normally press the said roller towards the disks c^{11} , bosses c^{16} being secured to the inner face 10 of the door by screws c^{17} , to afford a bearing point for the springs.

The feeding disks c^5 are of a circumference, such that a single rotation of the roller c^4 will feed a strip of paper corresponding in length 15 to a single print, and that part of the side walls a' in which is journaled the roller c^4 , is cut away from the remaining portion of the side walls and secured to the door a^9 so that when the door is removed, the roller c^4 is 20 removed therewith.

A shelf a^{21} is arranged below the bellows, the said shelf extending rearwardly to about the center of the roller c^4 , and a slit is arranged in the shelf to permit the passage of 25 the sensitized paper therethrough.

A knife D is arranged below the shelf, the said knife being triangular in shape as shown in Fig. 3, and being secured to the front of a bar d' slidably mounted in guideways d^7 30 secured to the side walls, the said knife being retained normally in retracted position by a spring d^6 secured to the bar d' and to the front wall of the casing. A shaft d^4 is journaled in the side walls of the casing below 35 the knife, and arms d^3 are adjustably secured to the shaft by set screws d^8 , the upper end of the arms being connected by links d^2 with the sliding bar d' , the said sliding bar being slotted as at d for receiving the links and the 40 upper end of the arms. A handle is secured to the shaft d^4 , outside of the casing, for manipulating the said shaft to move the sliding bar to cause the knife to sever the paper.

A tray e^{14} for containing a developing solution rests on the base within the casing at the 45 front thereof, the said tray being provided with an inclined rear wall e^{15} , for a purpose to be hereafter described. A device E for receiving the severed sheet and immersing it 50 in the tray of developing solution, is provided, the said device comprising a shaft or roller e journaled in the side walls of the casing, and having on its outer end a ratchet disk e^3 engaged by a pawl e^2 , the shaft being rotated 55 by means of a crank e' secured thereto.

Parallel spaced arms e^4 are secured to the shaft, the said arms being connected together by a cross rod e^5 adjacent to the shaft or roller, and by a second cross rod e^6 near 60 the free ends thereof. A plurality of fingers e^7 are pivotally mounted on the rod e^6 , and the front ends of the said fingers are journaled on a shaft e^8 , the fingers being connected on the opposite side of the cross rod 65 e^6 by a rod e^{16} , upon which are arranged a

plurality of spiral springs e^{17} , one spring being arranged between each pair of fingers to maintain them in spaced relation with respect to each other. Other fingers e^9 are journaled on the rod e^8 , a finger e^9 being provided for coöperating with each finger e^7 , said fingers e^9 being arranged below the fingers e^7 . The fingers e^9 are connected together by front and rear cross bars e^{12} , and are limited in their opening movement with 75 respect to the upper fingers by a U-shaped bar e^{10} having its arms pivoted to the arms 80 e^4 before mentioned.

It is evident from the description, that when the shaft e^4 is rotated in the direction of 85 the arrow in Fig. 2, that fingers e^7 , e^9 , will be moved towards the rear of the developing tray, and as they engage the inclined rear wall of the tray, they will be elevated by the same, being retained in a substantially horizontal position. When the arms e^4 attain a horizontal position, the front ends of the 90 fingers e^7 will engage the cross bar e^5 , and a continued rotation of the shaft will move the fingers into the position shown in dotted lines in Fig. 2, that is, with the opening between the series of fingers directly below the slit in the shelf a^{21} , so that when the exposed strip of sensitized paper is passed downwardly by the feed rollers, it will be inserted 95 between the series of fingers, and after being severed, will remain therebetween.

When the rotation of the shaft e is reversed, far enough so that the front ends of the fingers e^7 leave the cross rod e^5 , the free 100 ends of the fingers will have engaged the inclined rear wall of the tray, and the fingers will move into the developing fluid in a substantially horizontal position.

At the rear of the tray e^{14} , for containing 105 the developing fluid, is a second tray g^{17} for containing a fixing solution, and means are provided for receiving the developed print from the tray e^{14} and removing it to the tray g^{17} . The said means comprises a shaft or 110 roller G journaled in the side walls of the casing, and provided on its outer end with a handle g for rotating the said shaft, a spring g' being secured to a pin on the shaft and to the adjacent side wall for returning the shaft to 115 its original position. The shaft G is provided with parallel spaced arms g^2 , and the free ends of the arms are connected by links g^5 with a cross bar g^4 , sliding on guides g^3 arranged on the side walls of the casing. The 120 bar g^4 is provided on its lower face with brackets g^6 in which is journaled a roller g^7 provided with a plurality of radial pins g^8 , which project upwardly through slots g^9 in the sliding bar.

The cross bar g^4 is provided with fingers 125 g^{10} , and the roller g^7 is provided with spring fingers g^{11} for coöperating with the fingers g^{10} . Stop rods g^{12} , g^{13} are arranged at the limits of the travel of the cross bar, and are adapted to 130

be engaged by the pins g^8 before described, to rock the roller g^7 to move the spring fingers g^{16} towards and from the fingers g^{10} .

At about the center of the cross bar g^4 is provided a slot to the end wall of which is secured a spring g^{13} having an angular bend g^{14} at the end thereof, and the roller g^7 is provided with a projection g^{15} for engaging on either side of the angular portion of the

spring when the roller is rocked, in order to retain it in such position.

The relation of the stop rods and the pins g^8 , is such that when the sliding bar is moved forwardly, the roller g^7 is rocked to bring the spring fingers g^{16} into contact with the fingers g^{10} , whereby to grip the strip of paper, and when the stop rod g^{11} is engaged by the pins, the fingers are open, thus releasing the paper and permitting it to drop into the fixing solution.

In operation, the record to be copied is placed upon the support, which is adjusted to proper position, and the reflecting medium is adjusted to properly reflect the image on to the sensitized paper at the rear of the bellows. After the exposure is made, the shaft e is oscillated to bring the fingers of the receiving device into the position shown in dotted lines in Fig. 2, after which the roller carrying the feed disks is rotated one turn, thus moving the strip of paper downwardly so that the exposed portion passes between the series of fingers; the knife is now operated to sever the strip, after which the shaft e is rotated to lower the strip into the developing solution. A cross bar e^{20} is arranged transversely of the casing just below the knife, and in position for engagement by the fingers e^7 , when the receiving device is in proper position to receive the strip of paper from the feeding device.

After the image has been developed, the shaft e is rotated a sufficient distance to bring the lower fingers of the receiving device to the level of the upper edge of the developing tray, or slightly thereabove, after which the handle g of the shaft G is operated to move the sliding bar forwardly, and the stop rod g^{12} is arranged in such position as to close the fingers g^{16} after they have entered between the fingers of the receiving device, so that they are closed upon the strip of paper. A reverse movement of the handle g , moves the sliding bar to the opposite end of its travel, and opens the fingers g^{16} to permit the strip to drop into the fixing solution, where it may be left until removed from the machine.

The curtain c' is for the purpose of covering a portion of the strip when it is not desired to expose the entire length within the carrier chamber.

The partition a^{19} and the shelf a^{21} , form, together with the walls of the casing, a camera chamber, and this chamber, together

with the bellows and lens, forms a complete photographic camera. The complete device comprises in effect, a camera having above a receptacle for the roll of sensitized paper and below a chamber for developing and fixing the print; means being provided for passing the sensitized paper from the receptacle through the camera to the developing and fixing chamber.

It will be noticed that the means for receiving the strip of paper and immersing it in the developer, engage the opposite faces of the strip at spaced intervals throughout the full extent thereof, in order to properly immerse it. Were the strip only engaged at the center, or at the edges, it would be liable to curl, or a portion thereof would be liable to receive over-development. The arrangement of the fingers effectually prevents either of these defects.

The fingers of the means for receiving the paper from the feed rollers and immersing it in the tray, are of a length equal to the length of the paper whereby to properly support the said paper.

I claim:

1. In a device of the class described, the combination with the casing, having an opening in the front thereof, and a lens adjustably mounted in the opening, of an adjustable support below the opening, a reflecting medium adjustably mounted in front of the lens, a roller for the sensitized paper in the upper portion of the casing, feed rollers for moving the sensitized paper behind the lens, means for severing the exposed strip below the feed rollers, said means comprising a cross bar slidably mounted in the casing, a knife secured thereto, a shaft journaled below the cross bar and provided with spaced arms, links connecting the free ends of the arms and the cross bar, a spring normally retaining the cross bar in its retracted position, a tray for a developing fluid below the severing means, means for receiving the severed strip and immersing it in the tray, a tray for a fixing solution adjacent to the first named tray; and means for removing the strip from the receiving means and dropping it into the last named tray.

2. In a device of the class described, the combination with the casing, having an opening in the front thereof, and a lens adjustably mounted in the opening, of an adjustable support below the opening, a reflecting medium adjustably mounted in front of the lens, a roller for the sensitized paper in the upper portion of the casing, feed rollers for moving the sensitized strip behind the lens, means below the feed rollers for severing the exposed strip, a tray for a developing solution below the severing means, means for receiving the severed strip and immersing it in the tray, said means comprising a shaft journaled in the casing and provided with spaced

- arms, a rod connecting the free ends of the arms, a series of spaced fingers journaled on the rod, a series of spaced fingers below the first series, and coöperating therewith, said second series being pivoted to said first named series, means for limiting the opening movement of said second series with respect to the first series, a rod connecting the arms adjacent to the shaft in position for engagement by the connected ends of the fingers, and means for oscillating said shaft whereby to move the free ends of the fingers into position to receive the severed strip between the series of fingers, and to immerse it in the tray, a tray for a fixing solution adjacent to the first named tray, and means for removing the developed strip from the receiving means and dropping it into the second named tray.
3. In a device of the class described, the combination with the casing, having an opening in the front thereof, and a lens adjustably mounted in the opening, of an adjustable support below the opening, a reflecting medium adjustably mounted in front of the lens, a roller for the sensitized paper in the upper portion of the casing, feed rollers for moving the sensitized strip behind the lens, means below the feed rollers for severing the exposed strip, a tray for developing solution below the severing means, means for receiving the severed strip and immersing it in the tray, a tray for a fixing solution adjacent to the first named tray, and means for removing the developed strip from the receiving means and dropping it into said last named tray, said means comprising a cross bar slidably mounted in the casing, the front end of said cross bar being provided with a series of spaced fingers, and the body of the cross bar having a plurality of transverse slots therethrough, a roller journaled on the lower face of the cross bar, and provided with pins projecting through said slots, said roller being provided with a series of resilient fingers for coöperating with the first named fingers, a shaft journaled in the casing and provided with spaced arms, links connecting the free ends of the arms with the sliding bar, means for rotating said shaft, a spring for returning it to its original position, and spaced stop rods at each end of the travel of the cross bar for engaging the pins to rotate the roller whereby to open and close said fingers.
4. The combination with the casing, provided with a camera, and a receptacle for containing the sensitized paper, of means for passing the strip through the camera in position to receive an impression, means for severing the exposed strip, a tray for containing a developing solution in the casing, and means for receiving the severed strip and immersing it in the tray, said means comprising a plurality of spaced series of fingers, means for holding the fingers for receiving the strip, and for lowering them into the tray.
5. The combination with the casing, provided with a camera, and a receptacle for containing the sensitized paper, of means for passing the strip through the camera in position to receive an impression, means for severing the exposed strip, a receptacle for a developer, and means for receiving the strip from the severing means, and transferring it to the developer, said means comprising a plurality of spaced series of fingers, and means for holding the fingers in position to receive the strip therebetween, and for moving them into the developer.
6. The combination with the casing, provided with a camera, and a receptacle for containing the sensitized paper, of means for passing the strip through the camera in position to receive an impression, means for severing the exposed strip, a receptacle for a developer within the casing, means for receiving the severed strip and immersing it in the developer, a receptacle for a fixing solution within the casing, and means for removing the developed strip from the receiving means and dropping it into said last named receptacle, said means comprising a cross bar mounted in the casing for sliding movement toward and from the receiving means, said cross bar being provided with spaced fingers, a shaft journaled on the cross bar and provided with fingers for coöperating with the fingers of the cross bar, means for moving the cross bar toward and from the receiving means, and means for rocking the shaft at each end of its travel, whereby to close the fingers on the developed strip, and to release it when over the receptacle for the fixing solution.
7. The combination with the casing, provided with a camera, and a receptacle for containing the sensitized paper, of means for supporting the paper in position to receive an impression, a receptacle for a developer within the casing, and means for receiving the paper and immersing it in the developer, said means comprising a plurality of series of fingers, and means for holding the fingers with the series in position to receive the paper therebetween and for moving them into the developer.
8. The combination with the casing, provided with a camera, of means for supporting sensitized paper in position to receive an impression, a receptacle within the casing for holding a developer, means for receiving the paper from the camera, and immersing it in the developer, a receptacle for a fixing solution within the casing, and means for removing the developed paper from the receiving means and dropping it into said last named receptacle, said means comprising a plurality of series of fingers, one of said series being pivotally mounted with respect to the other

series, means for moving said fingers from the receiving means to the second named receptacle, and means for opening and closing the fingers at the ends of the travel thereof.

5. 9. The combination with the casing, provided with a camera, and means for supporting sensitized paper in the camera in position to receive an impression, of receptacles for a developing solution and a fixing solution, respectively, and means for receiving the paper from the camera, and placing it in the developing solution, and for removing it from the receiving means and placing it in the fixing solution, said means comprising fingers for grasping and conveying the paper.

10. The combination with the casing, provided with a camera, of means for supporting sensitized paper within the camera, in position to receive an impression, a tray for containing a developing solution within the casing, and means for receiving the paper and immersing it in the tray, said means comprising spaced fingers for receiving the paper therebetween, said fingers being of a length 25 equal to the length of the paper, whereby to properly immerse the same in the solution.

11. The combination with the casing, provided with a camera, of means for supporting sensitized paper within the camera, in position to receive an impression, means within the casing for containing a developing solution, means for receiving the paper from the camera and immersing it in the developing fluid, means for containing a fixing fluid 30 within the casing, and means for grasping the edge of the paper and withdrawing it from the receiving means and dropping it into the fixing solution.

12. The combination with the casing pro-

vided with a camera, of means for supporting sensitized paper within the camera in position to receive an impression, means for containing a developing solution within the casing, means for receiving the paper from the camera, and placing it in the developing solution, said means being arranged on both sides of the paper at spaced intervals throughout the full extent thereof, whereby to properly immerse it within the fluid, and means outside of the casing for manipulating said receiving means.

13. The combination with the casing, provided with a camera, of means for supporting sensitized paper within the camera in position to receive an impression, means for containing a developing solution within the casing, and means for receiving the paper from the camera and placing it in the developing solution, said means being arranged on both sides of the paper at spaced intervals throughout the full extent thereof, whereby to properly immerse it within the fluid.

14. The combination with the camera, of a developing chamber therebelow, means for supporting a strip of paper within the camera in position to receive an impression, means for containing a developing solution within the chamber, and means for receiving the exposed paper from the supporting means, and placing it in the solution, said means engaging the opposite faces of the paper at spaced intervals throughout the full extent thereof, whereby to properly immerse the paper.

GEORGE W. STEPHENSON.
